Term of patent 7 years

(Cl. D86—10)

Fig. 1

Fig. 3

Fig. 1 is an elevational view of a lipstick container showing my new design;

Fig. 2 is a top plan view thereof; and,

Fig. 3 is a development plan view of the surface ornamentation shown in Fig. 1.

The essential feature of the invention lies in the design motifs applied to the cover of the container.

I claim:

The ornamental design for a lipstick container, substantially as shown and described.
